Fig. 1

FIG. 2

FIG. 3

FIG. 4

FIG. 1 is a perspective view of a tire showing my new design, it being understood that the tread and sidewall patterns shown are repeated throughout the circumference of the tire, the opposite side of the tire being identical to that illustrated;

FIG. 2 is an enlarged fragmentary top plan view of a portion of the tire shown in FIG. 1;

FIG. 3 is a fragmentary transverse sectional view through the tire substantially on the plane indicated by the line 3—3 of FIG. 2; and

FIG. 4 is a fragmentary enlarged side view of the tire shown in FIG. 1.

I claim:

The ornamental design for a tire, substantially as shown and described.
